CONTROL MECHANISM FOR DRILLING MACHINES

Ivan F. Churchill, Fayetteville, N. Y.

Application April 14, 1945, Serial No. 588,345

4 Claims. (Cl. 77—32)

1

This invention relates to power drilling machines or drill presses and has for its object a simple, readily applied control mechanism therefore for withdrawing the drill when the drill encounters undue resistance that would or might break it were the drilling operation continued, as when the bore fills up with chips, withdraws the drill and again automatically feeds it in after the bore has been cleaned out by the withdrawal of the drill, combined with a mechanism to reverse or withdraw the drill, when the drill has bored to a predetermined depth and stop the drill from feeding at the end of its withdrawal, and to set a manual control by which the drilling operation is initiated to again start the feeding when the manual control is operated to drill a new hole.

The invention further has for its object a control mechanism which embodies a latch common to the feeding mechanism and to mechanism which determines the depth of the hole being bored, which latch is tripped by the throwing out of a self-resetting overload clutch in the spindle rotating mechanism, when the drill encounters undue resistance, and by depth determining mechanism when the hole is bored to a given depth.

The invention consists in the novel features and in the combinations and constructions hereinafter set forth and claimed.

In describing this invention, reference is had to the accompanying drawings in which like characters designate corresponding parts in all the views.

Figure 1 is a side elevation of a drill press or drilling machine having the feed and depth control mechanisms applied thereto.

Figure 2 is an elevation looking to the right in Figure 1, parts being omitted.

Figure 3 is an elevation looking to the left in Figure 1, parts being omitted.

Figures 4 and 5 are elevations of the feed mechanism for the spindle, partly in section, Figure 4 showing the parts including the manual in their starting position, and Figure 5 when in their running position.

This invention comprises, generally, a latch operable both by the throwing out of an overload clutch in the spindle rotating mechanism, which clutch throws out when the drill encounters undue resistance, and also by a depth determining mechanism operating to throw out the latch when the hole is bored to a predetermined depth, which latch controls reverse control members, as valves, for the reversible motor means of the drill feeding

2

mechanism, the tripping of the latch by the depth determining mechanism also effecting the same result, but in addition disabling the reversing mechanism, so that the machine does not repeat until a manual control member by which the drilling operation is initiated is again operated, as when a new hole is to be bored.

1 designates the standard, 2 the overhanging head, and 3 the table, of a drill press. 4 designates the axially movable and rotating spindle having a chuck 5 for the tool or drill 6. The mechanism for rotating the spindle, as here shown, includes an electric motor 7 and motion transmitting means between the motor and the drill spindle. This motion transmitting means includes axially aligned shaft sections 8, 9, which are connected together by a self-resetting overload clutch 10 (Figure 2), including an axially shiftable section or sleeve 11, which shifts axially under the overload against a suitable resetting spring 12, and means, as belts 13, 14, between the motor shaft and the drive shaft section 8 and between the driven shaft section 9 and the spindle, the belt 14 running over cone pulleys 15, 16 on the upper end of the driven shaft section 9 and on the upper end of the spindle 4. The opposing ends of the clutch sections are formed with cam-shaped jaws capable of ratcheting under an overload. The motor 7 and the shaft sections 8, 9 are carried by a plate or bracket 17 secured to the head 2. While the motor is in operation, obviously the drill will be rotated.

The mechanism for feeding the drill spindle comprises a reversible motor 18, a control member 19 therefor, and motion transmitting means between the movable member of this motor and the spindle for feeding the spindle axially in opposite directions. The actuation of the motor 18 is controlled by a motor 20, which is also a reversible motor, a manual control member 21 therefor, means operated by the movable member of the reversible motor 20, when it is actuated in one direction, (as when the manual member is operated manually to shift the reversing member 19 for the motor 18), to cause the motor 18 to be initially energized and operated to feed in the drill, and to move relatively to this reversing member 19 without operating it when moved in the other direction back to starting position, a latch operable to hold the control member 19 in its operated position, that is, the position to which it is moved upon the manual operation of the control member 21, and means operated by the shifting-out movement of the overload clutch 10 or the section 11 thereof under an overload for unlatch-

ing the latch, and thus permitting the control member 19 to return to its normal position, it being self-returnable, and means operated by the last feeding-in means when the hole has been bored a predetermined depth, for tripping the latch and also returning the manual control member 21 to its starting position. The self-returning or resetting means in the control member 19, for the purpose of illustration only, is shown as a spring 22 acting on a lever which operates the control member 19. This spring is, however, self-contained within the control member as is the spring 48 (Figure 4).

As the feeding and control mechanism is pneumatic or air-operated, the control motor 18 is shown as a reversible cylinder and piston motor. The motor 20 also is shown as a reciprocating or reversible cylinder and piston motor, and the control members 19 and 21 and also a control member 23 for the motor 20 are shown as valves.

The motion transmitting means operated by the movable member or piston 24 of the feed motor 18 is here shown as a rack 25 on the piston rod 26 and meshing with a pinion 27 on a sleeve 28 mounted on a rotating shaft 29 supported by and extending laterally from the head 2. The shaft 29 has a pinion, not shown, within the head 2 meshing with a rack on the spindle 4, as in any standard feed mechanism. The sleeve 28 is one section of an overload clutch and has cam or beveled jaws at its end, coacting with complementary jaws on another axially movable section 30 on the shaft 29, this section 30 being shiftable axially slightly against the action of a spring 31 under greater than normal torque or slight overload. The control motor 20, as before stated, is a cylinder and piston motor and its piston 32 has its rod 33 provided with a fork 34 which coacts with a shoulder 35 on a rod 36 extending parallel to the piston rod 33. The fork 34 and shoulder 35 form, in a general sense, a one-way clutch. The rod 36 is part of the operating connections for the reversing valve 19 and is here shown as connected to a lever 37 pivoted at its angle at 38 and having its angular arm located to press the stem 39 of the control valve 19 against the action of the spring 22. Owing to the one-way clutch device, the piston 32 actuates the rod 36 only in one direction, as to the left, and only when the manual member is operated or pulled out to open the valve 21.

40 designates a latch operated by the shiftable section 11 of the overload clutch 10 (Figure 2), and also by the spindle feeding mechanism, when the hole has been drilled to a predetermined depth. The latch is located to enter a notch 41 in the rod 36 when the rod is operated into position shown in Figure 5 from that shown in Figure 4, that is, operated to the left by the piston 32, upon the pulling of the manual operating rod 45 to the right. The latch, as seen in Figure 2, is a lever having one end located in the path of a collar 42 on the shiftable section 11 of the overload clutch 10. The action of the latch 40 is against the action of a returning spring 43. The cylinder or motor 18 is mounted on one side of the bracket 17 and the rod 36 is guided in a plate 44 depending from the motor 18 or the head at one end thereof. It is shown as extending through a sleeve of trip mechanism, to be described, which sleeve is slidable in the plate 44. As the piston 24 of the motor 18 moves to the left from starting position to move the drill downwardly, it sets an additional control or reversing valve 23 for the control motor 20, this valve be-

ing normally in position to exhaust air from the left end of the cylinder, when the piston 32 is moving to the right upon operation of the valve 21 from closed position (Figure 4) to open position (Figure 5), by the pulling of the manual member 45 to the right. As here shown, the reversing valve 23 is held in the position shown in Figures 4 and 5 at the start of the feeding movement of the drill, by a lateral arm 46 on the piston rod 26 of the feeding mechanism, the arm 46 pressing against the stem 47 of the valve 23. The valve 23 is biased by a spring 48 to press the stem 47 toward the arm 46 and to shift the valve when the arm 46 moves away from the valve stem 47 at the start of the feeding-in movement of the piston 24 and its rod 26 to the left. The arm 46 also again resets or reverses the valve 23 when the piston 24 and its rod 26 return to the right after each latch releasing operation by the overload clutch sleeve 11 or by the depth determining mechanism. As the piston 24 shifts to the left, the arm 46 will move away from the stem, letting the valve 23 shift to the left, so that it will assume a position wherein the air can exhaust from the right end of the cylinder bore of the control valve 20 and enter the left end past the valve 21, thus moving the piston 32 to the right and moving the fork 34 of the one-way clutch device away from the collar 35 on the rod 36, so that the rod 36 is free to shift to the right under the action of the spring 22 whenever the latch 40 is tripped.

Stop means are provided for limiting the downward feeding movement of the spindle, this being shown as including a shoulder, as a nut 49, adjustable along an upright screw 50 (Figure 3) parallel to the spindle and carried by a laterally extending bracket 51 which moves vertically with the spindle 4, the nut being located to come in contact with a stop 52 extending laterally from the head 2. The nut or shoulder 49 may be adjusted a predetermined distance from the stop, this distance being dependent upon the depth of the hole to be bored. When the downward movement of the drill is stopped by the nut 49 engaging the stop 42, the overload clutch section 30 will shift axially slightly permitting additional movement of the feed mechanism relative to the drill spindle.

50 The depth determining mechanism includes mechanism operated by the feeding-in movement of the drill spindle or its motion transmitting means, as the piston rod 26, for tripping the latch 40, and thus permitting the valve 19 to reverse and permit the air to enter the left end of the cylinder 18. This depth determining mechanism includes an adjustable shoulder 53 on a sleeve 54 slideable on the control rod 36 and the arm 46 on the piston rod 26. The shoulder 53 constitutes an adjustable nut and a lock nut, and their adjusted position along the sleeve 54 determines the depth of the hole to be drilled by cutting out the feed mechanism. The sleeve 54 has a shoulder or head 55 at its end for thrusting against a sleeve 57A on the rod 36, the sleeve being slideable in the bracket 44. It is provided with a cam head 57 which moves into engagement with the latch 40 to trip it and thus permit the valve 19 to again reverse, and hence stop the feeding movement. There is also a connection between the sleeve 57A and the manually operated control rod 45 to shift this rod to the left and shift the valve 21 thereon from open position into starting or cut-off position, so that the piston 24 of the cylinder 18 withdraws the drill. The feed-

ing-in mechanism, however, will not be operated, because the air is now cut off from passing to the bore of the control motor 20, as the valve 21 is in closed position and will remain in closed position, until manually operated for boring a new hole. This connection includes an arm 57B on the sleeve 57A located to coact with a collar 56 on the manually operated rod 45. The movement of the sleeve 57A and the cam 57 is against the action of a returning spring 58, and there is sufficient initial clearance between the cam 57 and the latch 40 to permit the arm 57B to pick up the shoulder 56 and return the rod 45 to the left and the valve 21 to closed position just ahead of the time the cam 57 trips the latch. The shoulder 53 and the nut 49 must be adjusted in accordance with the depth of the hole to be bored, so that the arm 46 engages the shoulder 53 approximately when the nut 49 engages the stop 52. The overload clutch section 30 (Figure 3) permits this continued movement of the piston rod 26 and arm 46 relatively to the stop spindle, so that the sleeve 54 can operate to shift the cam 57 and the rod 45 after the spindle is stopped from feeding axially. The positive stop mechanism 49, 50, 51 may be omitted. Upon the releasing of the latch 40, and hence the reversing of the valve 19, and the resetting of the manual control rod 45 in its position assumed when the valve 21 is closed, the machine is prevented from repeating its operation, when the hole has been bored to a predetermined depth. To start the machine to bore another hole, the operator must again pull the rod 45 to the right to open the valve 21.

In operation, the shoulders 49, 53 having been set for the depth of the hole and with the parts in the position shown in Figure 4, and also the shoulder 53 on the sleeve 54 adjusted in accordance with the shoulder 49, the operator pulls out or to the right the rod 45, this shifting the control valve 21 to open the intake port for the control member 20, so that air will pass to the right hand side of the piston 32 and actuate the piston 32 to the left, causing the fork 34 on the piston rod 33 to pick up the shoulder 35 on the rod 36 and thus automatically operate the reversing valve 19 for the cylinder 18. This permits air to enter the right end of the cylinder 18 and actuate the piston 24 to the left, which through the piston rod 26, rack and pinion 24 and 27, shaft 29 and overload clutch 28, 30, causes the drill spindle 4 to feed downwardly. During this movement, the arm 46 on the piston rod 26 moves away from the stem 47 of the spring biased valve 23 permitting this valve to reverse, so that the left hand end of the cylinder bore of the control member 20 is free to receive air and the right hand end is open to exhaust, and the piston 32 moves to the right, moving the shoulder 34 away from the collar 35. The latch 40 holds the rod 36 and the reversing valve 19 in their operated positions, the latch 40 having snapped into the notch 41 during the movement of the rod 36 to the left. Whenever the drill encounters undue resistance to its rotation, the latch 40 will be moved out of its notch 41, permitting the valve 19 to reverse under the influence of the spring 22, thus reversing the piston 24, so that it moves to the right, and in so doing, withdraws the drill through the piston rod 26 and feed mechanism described. The overload clutch 10 is self-resetting. When the piston rod 26 returns to the right, in which position the arm 46 again resets the valve 23, air will again enter the right

hand end of the cylinder bore of the valve motor 20 and move the valve piston 32 to the left, thus again reversing the valve 19 from the position shown in Figure 4 to that shown in Figure 5, so that the piston 24 will again move to the left, feeding the drill spindle 4 downwardly through the piston rod 26 and motion transmitting means operated thereby. When the shoulders 49 of the stop mechanism stop the downward feeding of the drill spindle 4 by engaging the stop 52, the overload clutch 30 will slip or throw out slightly, and in so doing permit the arm 46, which has been feeding continuously with the piston rod 26 to contact the shoulder 53 on the sleeve 54 and moves the shoulder 55 to successively shift the manual rod 45 and the cam 57 to trip the latch 40. The shifting of the manual rod 45 shifts the valve 21 to cut-off position, stopping the machine against repeated operation, until the rod 45 is again pulled outward to the right.

During the boring of the hole, the drill may be stopped several times by encountering undue resistance causing the throwing out of the overload clutch, and the drilling automatically resumed after each withdrawal. When the hole is bored to a predetermined depth, owing to the ratcheting clutch 30, the drill may continue to rotate for a brief period to clean out the bottom of the hole and the chips before being withdrawn, while the clearance is being taken up between the cam 57 and the latch 40.

What I claim is:

1. In a control for drill presses having a drill spindle, power operated mechanism for rotating the drill spindle, feeding mechanism for the drill spindle including a reversible cylinder and piston motor, a reversing control valve therefor having biasing means to shift it into position to cause the piston to move in one direction to withdraw the spindle, and a manual operating member for controlling the operation of the control valve against the biasing means to cause the feeding in of the spindle; the combination of a self-resetting overload clutch included in said spindle rotating mechanism, a latch operable to hold the reversing control valve in its position occupied when the drill spindle is being fed into the work, means operated by the shifting out of the overload clutch to release the latch, and means operated by the feeding-in mechanism for tripping the latch when the drill has bored to a predetermined depth, thereby permitting the reverse control valve to return to starting position under the influence of its biasing means and return the manual to its initial starting position.
2. In a control for drill presses having a drill spindle, power operated mechanism for rotating the drill spindle, feeding mechanism for the drill spindle including a reversible cylinder and piston motor, a reversing control valve therefor having biasing means to shift it into position to cause the piston to move in one direction to withdraw the spindle, and a manual operating member for controlling the operation of the control valve against the biasing means to cause the feeding in of the spindle; the combination of a self-resetting overload clutch included in said spindle rotating mechanism, a latch operable to hold the reversing control valve in its position occupied when the drill spindle is being fed into the work, means operated by the shifting out of the overload clutch to release the latch, power means controlled by the spindle feeding mechanism and by the manual control member when in

its operated position for operating the reversing valve against the biasing means, and means operated by the feeding in mechanism for tripping the latch when the drill spindle has been fed a predetermined distance and for returning the manual member from its manually operated position to its initial position.

3. In a control for drill presses having a drill spindle, power operated mechanism for rotating the drill spindle, feeding mechanism for the drill spindle including a reversible cylinder and piston motor, a reversing control valve therefor having biasing means to shift it into position to cause the piston to move in one direction to withdraw the spindle, and a manual operating member for controlling the operation of the control valve against the biasing means to cause the feeding in of the spindle; the combination of a self-resetting overload clutch included in said spindle rotating mechanism, a latch operable to hold the reversing control valve in its position occupied when the drill spindle is being fed into the work, means operated by the shifting out of the overload clutch to release the latch, power means controlled by the spindle feeding mechanism and by the manual control member when in its operated position for operating the reversing valve against the biasing means, means operated by the feeding mechanism for tripping the latch when the drill spindle has been fed a predetermined distance and for returning the manual member from its manually operated position to its initial position, means for stopping the feeding in of the drill spindle when the hole has been bored to a predetermined depth, the feeding-in mechanism including a yielding joint permitting a portion of said mechanism to continue the feeding movement farther slightly when the drill spindle is stopped, and means operated by the additional feeding movement for tripping the latch and returning the manual member from its manually operated position to its initial position.

4. In a control for drill presses, the combination with a drill press having a rotating spindle,

power motion transmitting means for rotating the spindle including an overload clutch, spindle feeding mechanism including a reversible motor, motion transmitting means operated thereby for feeding the spindle axially, and a reversing control member for the motor including a self-returnable shiftable part, a second reversible control motor, and means operated thereby for operating the control member for the first motor into one position against its self-returnable means, a manual control member operable in one direction manually for initiating the operation of the second motor to operate the control member for the first motor in one direction against its self-returning means; of a latch operable to hold the control member for the first motor in the position in which it is operated by the second motor upon operation of the manual control member, an automatically operable reversing control member for the second motor and means operated by the feeding mechanism during the feeding-in movement thereof to control the operation of the reverse control member of the second motor when the feeding movement of the spindle has been initiated and resetting the same when the feed mechanism returns to starting position, means operated by the overload clutch when overloaded to release the latch and thereby permitting the first control member to reverse, and means operated by the feeding mechanism for returning the manual control member to its starting position and tripping the latch when the feeding mechanism has fed the drill spindle a predetermined distance.
